UNITED STATES PATENT OFFICE

119,599

DESIGN FOR A DISPLAY BOX

Joseph F. Rioux, Attleboro, Mass.

Application May 17, 1939, Serial No. 85,055

Term of patent 7 years

To all whom it may concern:

Be it known that I, Joseph F. Rioux, a citizen of the United States of America, residing of Attleboro, county of Bristol, State of Massachusetts, have invented a new, original, and ornamental Design for a Display Box, of which the following is a specification, reference being had to the accompanying drawing, forming a part thereof.

Fig. 1 is a top plan view of a display box with the cover raised;

Fig. 2 is a sectional view, taken along line 2—2 of Fig. 1; and

Fig. 3 is a side elevational view of the display box with the cover shown in broken lines and in closed position, showing my new design.

The dominant feature of the design resides in the portion of the display box shown in full lines.

I claim:

The ornamental design for a display box, substantially as shown and described.

JOSEPH F. RIOUX.
